Primary Examiner — Darlington Ly*(74) Attorney, Agent, or Firm* — Knobbe, Martens, Olson & Bear, LLP(57) **CLAIM**

The ornamental design for a bicycle frame, as shown and described.

DESCRIPTION

FIG. 1 is a perspective view showing a bicycle frame that embodies the design.

FIG. 2 is another perspective view of the bicycle frame of FIG. 1.

FIG. 3 is a right side view of the bicycle frame of FIG. 1. The left side view is a mirror image of the right side view.

FIG. 4 is a front view of the bicycle frame of FIG. 1.

FIG. 5 is a rear view of the bicycle frame of FIG. 1.

FIG. 6 is a top view of the bicycle frame of FIG. 1; and,

FIG. 7 is a bottom view of the bicycle frame of FIG. 1.

The broken lines in the drawings illustrate portions of the bicycle frame that forms no part of the claimed design.

1 Claim, 5 Drawing Sheets(56)
